(57) **CLAIM**

The ornamental design for a novelty snow globe figurehead, as shown and described.

DESCRIPTION

FIG. 1 is a perspective view of a novelty snow globe showing my new design;

FIG. 2 is a left side elevational view thereof;

FIG. 3 is right side elevational view thereof,

FIG. 4 is a front elevational view thereof;

FIG. 5 is a rear elevational view thereof; and,

FIG. 6 is top plan view thereof.

There is no bottom view, as the bottom is merely a base of the snow globe, which provides no view up into the snow globe of the figurehead depicted therein.

The broken line showing around the figure head is included for the purpose of illustrating environment and forms no part of the claimed design.
